Per Atty:

UNITED STATES PATENT OFFICE.

JOHN B. WOOD, OF MONTREAL, QUEBEC, CANADA.

DESIGN FOR A JEWELER'S STAND.

SPECIFICATION forming part of Design No. 12,752, dated February 7, 1882.

Application filed December 23, 1881. Term of patent 2½ years. Patented in Canada December 21, 1881.

To all whom it may concern:

Be it known that I, JOHN BAXTER WOOD, of Montreal, Canada, a subject of the Queen of Great Britain, have invented and produced 5 a new and original Design for Jewelers' Stands for Holding and Displaying Rings or Chains, of which the following is a specification, reference being had to the accompanying photograph, forming part thereof.

- 10 This photograph shows a part side and part front view of my newly-designed stand. The leading feature of my design is the shape of the stand in which the rings are inserted and upon which the chains lie.
- 15 I make the frame A of the stand in vertical section a double curve, with a transverse staff or rod, B, at the top and another, B', at the bottom, so as to resemble a scroll or unwound map, &c. This frame, which is suitably sup-

ported in a nearly vertical position, is covered 20 on its upper surface with velvet, satin, plush, or other suitable material of the color desired. Within a border, which may be formed of twisted cord of variegated colors, are set the rings, arranged in any suitable way, the curved 25 outline of the stand allowing them to be placed at the angle best suited to display them. The chains may also be suspended from hooks C, suitably fixed on the top of the stand.

What I claim is—

The jeweler's ring and chain stand consisting of the frame A, shaped as shown, with transverse rods B B' top and bottom.

JOHN BAXTER WOOD.
